United States Patent Office

Des. 220,855
Patented June 1, 1971

220,855

TONGUE DEPRESSOR

Montague Richard Duval, St. Petersburg, Fla., assignor
to Concept, Inc., St. Petersburg, Fla.

Filed Feb. 5, 1970, Ser. No. 21,279

Term of patent 14 years

Int. Cl. D24—03

U.S. Cl. D83—12

FIG. 1

FIG. 2

FIG. 3

FIG. 5

FIG. 6

FIG. 4

FIG. 1 is a top perspective view of the tongue depressor, showing my new design;

FIG. 2 is a top plan view of the same;

FIG. 3 is a side elevation thereof.

FIG. 4 is a bottom plan view of the tongue depressor;

FIG. 5 is a front end view; and

FIG. 6 is a rear end view of the tongue depressor.

I claim:

The ornamental design for a tongue depressor, as shown.
